CENTRIFUGAL FLUID JET PULVERIZER

Albert C. Hobbie, Moorestown, N. J., assignor to
 International Pulverizing Corporation, Camden,
 N. J., a corporation of New Jersey

Application September 1, 1937, Serial No. 161,934

3 Claims. (Cl. 83—46)

This invention relates to apparatus for pulverizing or size reduction of solid materials by centrifugal fluid jet action, and particularly to pulverizing apparatus wherein jets of gaseous fluid 5 are introduced at high velocity into an annular grinding zone in an outer portion of a treatment chamber of circular cross section, said grinding zone containing material to be pulverized in the form of discrete small pieces. The high velocity 10 fluid jets, or at least most of them, are introduced in directions inclined forwardly in one direction with respect to radii of the treatment chamber, so as to maintain the fluid in the chamber in rapid whirling motion in the direction of 15 such forward inclination, either clockwise or counterclockwise. The grinding zone is of limited axial length and is confined by peripheral portions of the chamber walls enclosing said zone at its outer circumference and at both axial ends, 20 and gaseous fluid is continually withdrawn inwardly from the grinding zone and discharged from the treatment chamber, preferably through a centrally disposed fluid outlet. The gaseous fluid thus has a general inwardly spiralling movement 25 within the treatment chamber, and the material to be pulverized is preferably continually introduced into the moving fluid within the treatment chamber.

The high velocity fluid jets effect a reduction 30 of particle size of the material under treatment by impact and attrition of particles against one another and against the chamber walls, while at the same time causing the charge of material to rotate rapidly within the grinding zone in the 35 direction of the whirling movement of the fluid. Due to the centrifugal effects resulting from the rapid rotation of the charge within the grinding zone, the larger particles are caused to circulate in said zone where they come repeatedly under 40 the influence of the introduced high velocity jets and are thus repeatedly subjected to the size reducing action produced thereby, while the material which is sufficiently reduced in size is entrained by the gaseous fluid as it spirals inwardly 45 toward the centrally disposed fluid outlet.

The entraining action of the inwardly spiralling gaseous fluid exerts on the suspended particles of the circulating material within the pulverizing zone a radially inward component opposing the 50 radially outward component due to centrifugal action, and continuously removes from the grinding zone particles which are sufficiently reduced in size, entraining such particles toward the fluid outlet and effecting a very intense fluid-sweeping action of the charge within the chamber, to-

gether with a high degree of centrifugal classification of the entrained material. A portion of the chamber radially inwardly from the grinding zone may communicate with an axially extended centrifugal product collector of smaller diameter 5 than the chamber, which utilizes the whirling energy of the gaseous fluid entering said collector to separate a considerable portion of the entrained material from the carrier fluid, while the fluid, more or less freed of such material, may be 10 discharged through the axially or centrally disposed fluid outlet which is of smaller diameter than the collector and may, if desired, be subjected to a further separating action outside the chamber to remove a further quantity of solid 15 material therefrom. The outer circumference of the centrifugal product collector is preferably spaced a considerable distance radially inward from the annular grinding zone into which the high velocity fluid jets are introduced, so that 20 the above described centrifugal classifying action is maintained not only within the grinding zone but also in an intermediate classifying zone, whereby particles which have not been sufficiently 25 reduced in size are effectively prevented from inward entrainment to the product collector or to the central fluid outlet and are caused to recirculate in the grinding zone until sufficiently reduced. In some cases, the above described centrifugal product collector may be omitted, and all 30 of the material which is sufficiently reduced may be discharged with the entraining gaseous fluid through the centrally disposed outlet and may be separated and collected in any suitable manner outside the treatment chamber.

It is generally convenient and preferable to introduce the material to be pulverized into the treatment chamber at one or more positions inwardly of the zone of action of the high velocity jets, and preferably adjacent but within the inner 35 boundary of the grinding zone, so that any material which is already sufficiently reduced to be entrained and carried inwardly by the spiralling fluid is not caused to be subjected to further grinding action, while particles of larger size are 40 caused by centrifugal action to move outwardly into the grinding zone. Furthermore, it is generally convenient to introduce this material into the treatment chamber in suspension in a gaseous fluid having a component of motion in the direction 45 of whirling fluid movement induced by the high velocity fluid jets.

The present invention is concerned with the grinding zone of such fluid jet pulverizing apparatus, and particularly with the manner in which 50

the high velocity fluid jets are introduced into said zone and the configuration of the peripheral walls of said zone, and it will be understood that the features of this invention may be employed in 5 any centrifugal fluid jet pulverizing apparatus of the general type above described, irrespective of the manner or position of introducing the material to be pulverized and of the manner in which the fluid and pulverized material are removed 10 from the grinding zone and separated from one another.

The principal objects of the invention are to provide for highly effective utilization of the energy of the high velocity fluid jets in effecting 15 size reduction of the material by impact and attrition; to provide improved means for bringing the material under the influence of the high velocity fluid jets; and to minimize or reduce the wear on the walls of the grinding zone.

20 In centrifugal fluid jet pulverizers the diameter of the openings through which the high velocity fluid jets are introduced into the grinding zone is small compared to the axial length of said zone. As the circulating material is more or less 25 free to distribute itself throughout the axial length of the grinding zone, it will be evident that only a small portion of this material will be directly intercepted by a high velocity jet in moving past the angular position of the jet. Consequently, only a relatively small or limited portion 30 of the circulating material is intercepted by the fluid jets during each complete rotation of the material about the axis of the treatment chamber. It is possible for some material to circulate for considerable lengths of time in planes 35 axially removed from the plane or planes of the jets, and it is necessary to depend upon random mixing induced by frictional eddies at the periphery of the chamber in order to ultimately bring 40 all the material within the zone of action of the jets.

An important object of the invention, therefore, is to provide jet openings so directed into the annular grinding zone that the high velocity 45 fluid jets issuing from said openings will cause a positive circulatory motion within said grinding zone in radial planes through the axis of the treatment chamber, to be superimposed upon the general circulation of the charge around the axis 50 of the chamber, in order to direct the circulating material positively into the zones of action of the issuing jets.

A further object of the invention is to provide, in a pulverizing apparatus having jet openings so directed as to superimpose the above 55 described circulatory motion in radial planes upon the rotation of the material about the axis of the chamber, a treatment chamber in which the peripheral wall portions extending around 60 and at both axial ends of the grinding zone are of curved configuration in radial planes through the axis conforming generally to the curvature of the superimposed circulatory motion produced by the fluid jets, so as to assist in maintaining such 65 circulatory motion of the material and in the resulting positive movement of the material into the zones of action of the jets.

In centrifugal fluid jet pulverizers having one or more pairs of opposed jet openings so directed 70 as to maintain the rotation of the material in the chamber and having opposed axial components directed toward each other to cause impacts of particles projected by the jets, it is found that when these jets are located sufficiently close 75 to the periphery of the chamber to intercept and

act upon the circulating material, there is a localized region of intense wear at the peripheral walls adjacent the intersection of two such opposed jets due to the vigorous sand blasting action resulting from the random scattering of impacting particles. 5

A further object of the present invention, in a preferred embodiment, is to provide a centrifugal fluid jet pulverizer having one or more pairs of opposed jet openings, directed as above described 10 but located radially inwardly from the periphery of the treatment chamber a sufficient distance to greatly reduce or minimize the localized wear on the peripheral walls resulting from sand blasting action due to scattering of the impacted particles. In order to effectively reduce or avoid this localized wear when using opposed jets, it is necessary that not only the jet openings themselves, but also the positions of intersection of the opposed jets, be inwardly removed from the 15 periphery of the chamber. In centrifugal fluid jet pulverizers of the prior art, jets so located would be relatively ineffective because the material to be pulverized would circulate largely adjacent the periphery of the chambers and outside 20 the zone of action of the jets.

Accordingly, it is a further object of my invention to provide, in conjunction with opposed fluid jets located inwardly from the periphery of the chamber as above described, other jet openings adjacent the periphery of the chamber and so disposed and directed as to superimpose upon the general rotative motion of the circulating material about the axis of the chamber a component of motion in a radial plane through the 30 axis of the chamber to direct the material positively into the zone of action of the opposed jets, thus effectively utilizing the increased shattering and pulverizing effect of the opposed jets while eliminating or minimizing the localized 35 wear which would result if portions of the chamber walls were closely adjacent the intersection of the opposed jets.

The accompanying drawings illustrate forms of 40 centrifugal fluid jet pulverizing apparatus in accordance with my invention, and referring thereto:

Fig. 1 is a vertical section through the axis of a preferred form of such apparatus, with certain parts broken away; 50

Fig. 2 is a partly sectional plan view on line 2—2 in Fig. 1, with the top of the material supply passage partly broken away;

Fig. 3 is an enlarged vertical section on line 3—3 in Fig. 1; 55

Fig. 4 is a partial vertical section of a modified form of apparatus; and

Fig. 5 is a partial plan view of the form of apparatus shown in Fig. 4, showing an alternative arrangement of the jet openings. 60

The apparatus shown in Figs. 1 to 3 comprises a casing of circular cross section enclosing a treatment chamber and including a top section 1, a bottom section 1', and an intermediate ring section 2 interposed between the top and bottom 65 sections. The sections are shown as flanged exteriorly at their meeting faces, as at 3, and secured together by means of tie bolts 4.

Portions of the top and bottom sections inwardly from the peripheries thereof are formed 70 as flat top and bottom walls 5 and 5' while the peripheral portions 6 and 6' thereof are curved in an inwardly concave fashion, preferably substantially along arcs of circles in radial planes through the axis of the chamber, as shown in 75

Fig. 1, from the juncture thereof with the flat top and bottom portions 5 and 5' to their outer edges where they join the ring section 2. The top and bottom sections are provided with annular fluid pressure manifolds 7 and 7' disposed exteriorly of the curved wall portions 6 and 6' respectively and having fluid inlets 8 and 8'. The intermediate ring section 2 forms a peripheral wall whose upper and lower portions 9 and 9' are curved, in radial planes through the axis of the chamber, preferably substantially along arcs of circles tangent to the curved wall portions 6 and 6' respectively and meeting one another at 11. This section is also provided with an annular pressure manifold 12 disposed exteriorly of the walls 9 and 9' and having a fluid inlet 13.

It will be understood that the above described sectional construction of the casing is not essential to the invention, and is shown merely for the purpose of simplifying fabrication and assembly and at the same time facilitating access to the interior of the casing for cleaning, inspection or other purpose.

25 The outer portion of the treatment chamber within the casing may be defined as an annular grinding zone, and it will be seen that the curved peripheral wall portions 6, 9, 9' and 6' extend around and at both axial ends of this grinding zone. These curved wall portions are provided with fluid jet openings communicating with the pressure manifolds and adapted to introduce high velocity fluid jets into the grinding zone, and said jet openings are so positioned and directed that the fluid jets issuing therefrom will maintain the general rotation or whirling motion of the material to be pulverized about the axis of the chamber and will also superimpose thereon a positively circulatory motion having components in radial planes passing through the axis of the chamber. As may be seen from Figs. 1 and 2, I have shown four sets of jet openings, at 90° intervals around the circumference of the chamber, the position of the respective sets of jet openings being indicated at A, B, C and D in Fig. 2. It will be understood, however, that any desired number and angular spacing of these jet openings around the circumference of the chamber may be employed.

50 The annular grinding zone may be considered as comprising two portions Z and Z' lying respectively above and below a median horizontal plane through the circular line at 11 defined by the juncture of the upper curved wall portion 9 and the lower curved wall portion 9' of the intermediate casing section 2. The upper portion of this grinding zone is defined by the curved wall portions 6 and 9 whose center of curvature, in any plane passing through the axis of the chamber (such as the plane of Fig. 1) is indicated at O, while the lower portion of this zone is defined by the curved wall portions 6' and 9' whose center of curvature in such a plane is indicated at O' and is axially spaced from the point O. 55 Each set of jet openings is shown as comprising a plurality of openings such as 14a, 15a, and 16a at different angular positions about the center O, for delivering gaseous fluid at high velocity into the upper portion of the grinding zone, the direction of the axis of each opening having a component inclined inwardly toward the interior of the treatment chamber and forwardly in one direction (clockwise in Fig. 2) with respect to the radius of the treatment chamber at the position of that opening, as indicated in Fig. 2 by the

dotted projection traces of these axes upon a horizontal plane, and also having a component inclined inwardly toward the interior of the treatment chamber and in one direction (clockwise at the left side of Fig. 1) with respect to a radial line from the position of that opening to the center of curvature O, as indicated in Fig. 1 by the dotted projection traces of said axes upon a radial vertical plane passing through the axis of the treatment chamber. Each set 10 of jet openings further comprises a plurality of openings 14a', 15a' and 16a' at different angular positions about the center of curvature O', for delivering gaseous fluid at high velocity into the lower portion of the grinding zone, the axis 15 of each of these openings having a component of forward inclination with respect to radii of the treatment chamber in the same manner as above described and also having a component inclined inwardly toward the interior of the treatment 20 chamber and in a direction opposite to that of the jet openings in the upper portion (counterclockwise at the left side of Fig. 1) with respect to a radial line from the position of that opening to the center of curvature O', as also indicated in Fig. 1 by the dotted projection traces 25 of the jet axes upon a radial vertical plane passing through the axis of the treatment chamber. The jet openings 15a and 16a are shown as extending through the curved wall portion 6 of 30 the upper casing section 1 and communicating with the pressure manifold 7; the jet openings 14a and 14a' as extending through the curved wall portions 9 and 9' respectively of the intermediate casing section 2 and communicating with 35 the pressure manifold 12; and the jet openings 15a' and 16a' as extending through the curved wall portion 6' of the lower casing section 1' and communicating with the pressure manifold 7', but it will be understood that any desired arrangement of pressure manifolds or conduits may be employed for placing these jet openings in communication with a source of fluid under pressure.

The component of inclination of the jet openings forwardly with respect to radii of the treatment chamber causes the high velocity fluid jets introduced therethrough to maintain a general whirling movement of gaseous fluid and material to be reduced about the axis of the treatment 45 chamber, in a clockwise direction, as indicated by the arrow in Fig. 2, while the components of inclination of the several openings with respect to radii through the centers of curvature O and O' of the walls of the grinding zone cause such fluid jets to superimpose upon this general whirling movement a circulatory motion in radial vertical planes through the axis of the treatment chamber. This latter motion is clockwise in the upper portion, and counterclockwise in the lower 50 portion of the grinding zone at the left side of Fig. 1, as indicated by the arrows in that figure.

It will be observed that the jet openings 16a and 16a' are substantially opposite one another in a direction parallel to the axis of the treatment chamber, and have opposed components directed toward each other and parallel to said axis, that is, the opening 16a has a component directed vertically downward and the opening 16a' has a component directed vertically upward. 55 Since these openings also have components directed forwardly in the direction of general whirling movement about the axis of the treating chamber, the fluid jets introduced therethrough will be inclined toward each other as indicated 60 65 70 75

in Fig. 3 by the dotted projection traces of the jet axes upon the plane of said figure, and will intersect one another at a position somewhat beyond the position of said openings in the direction of said whirling movement, as at X.

It will be understood that as the fluid jets enter the treatment chamber they will gradually expand in diameter. The jet openings shown at 14c', 15c' and 16c' represent openings of the set C corresponding to the openings 14a', 15a' and 16a' of set A. The fluid jet issuing from opening 16c' will expand as indicated, for example, at J, and the position of intersection thereof with the opposing jet (from opening 16c in Fig. 1) 10 may be as indicated, for example, at X' in Fig. 2. The opposed openings, such as 16a, 16a', and 16c, 16c', are located radially inwardly from the periphery of the treatment chamber, and it will be seen that the positions and directions of these 20 openings are such that the oppositely directed jets issuing therefrom will intersect one another at positions (such as X') which are also inwardly removed from the periphery of the chamber, thereby avoiding excessive wear on the walls of 25 the chamber due to the sand blasting action of impacting particles acted upon by such jets, as discussed above. The remaining jet openings of each set, such as openings 14a, 15a, 14c' and 15a' of set A and openings 14c, 15c, 14c' and 30 15c' of set C, are located closer to the periphery of the treatment chamber and at greater radial distances from the axis of the chamber than the openings 16a, 16a', 16c and 16c' of the corresponding sets, so that the fluid jets issuing from 35 said other jet openings are adapted to act upon the material which tends to accumulate by centrifugal action in the peripheral portions of the grinding zone, i. e., in the portions of said zone which are at the greatest radial distance from 40 the axis of the chamber. Thus, as will be described more fully hereinafter, by locating the jets of each set at a plurality of different distances from the axis of the casing, the material which is carried by centrifugal force outwardly 45 toward the periphery of the casing is picked up and positively directed into positions where it can be acted upon by jets inwardly removed from the periphery.

The other parts of the apparatus may be substantially as described in U. S. Patent No. 2,032,827 and are shown as comprising a centrifugal product collector 21 associated with and extending through the bottom wall 5', a centrally disposed fluid outlet passage 22 associated with 50 55 and extending through the top wall 5, and suitable means for feeding divided solid material into the treatment chamber. The centrifugal product collector 21 is of materially less diameter than the inner diameter of the grinding zone and opens 60 at its upper end 23 into the treatment chamber. Any suitable storing means may be provided at the lower end of the centrifugal product collector to provide for either intermittent or continuous discharge of collected material therefrom, preferably 65 in such manner as to substantially avoid inflow or outflow of air or gas. The outlet pipe 22 is of smaller diameter than the product collector 21 and is shown as opening at its lower end 24 into the interior of the treatment chamber at a position somewhat above the upper end 70 of the product collector.

The means for introducing divided solid material is shown as comprising an annular supply passage or manifold 25 associated with the top wall 5 and communication with the interior of 75

the treatment chamber through a plurality of openings 26 in said top wall, said openings being inclined downwardly and forwardly in the direction of the above described whirling movement of the gaseous fluid within the chamber around the axis thereof, a passage 27 through which a suitable gaseous fluid is supplied to the annular chamber 25 in a downwardly and forwardly inclined direction conforming to the direction of said whirling movement and provided with means such as a nozzle 28 for creating a reduced pressure therein, and a hopper 29 for feeding divided solid material into the passage 27 at the position of such reduced pressure.

In operation of the apparatus, a gaseous fluid at high pressure is continuously supplied to the manifolds 7, 7' and 12 through the inlets 8, 8' and 13. Such fluid may be either air or other permanent gas from a compressor or other suitable source of high pressure, or may be dry steam from a high pressure boiler, and may be introduced, for example, at a pressure between about 50 and 500 pounds per square inch or more. This gaseous fluid is delivered from the manifolds through jet openings 14a, 15a, 16a, etc., in the form of high velocity jets directed as above described. The jet openings are of sufficiently small size with relation to the dimensions of the apparatus, so that fluid jets of the desired high velocity may be introduced therethrough without causing an excessive total flow of gaseous fluid through the treatment chamber which might prevent classification at the desired particle size. While the jet openings are shown as being simply openings through the walls of the treatment chamber, it will be understood that suitable replaceable nozzles having small orifices may be provided if desired.

As explained above, the fluid jets serve not only to maintain the whirling movement of the contents of the treatment chamber around the axis thereof but also to superimpose upon this general whirling motion a circulatory motion in radial vertical planes passing through the axis of the chamber. Due to the inward movement of the fluid toward the outlet pipe 22, the resulting composite motion of the fluid is further modified to produce an inward spiralling thereof.

The divided solid material to be treated is introduced through the annular supply passage 25 as above described and is delivered, in suspension in the gas supplied through passage 27, through the inclined material supply openings 26, so that as the material enters the treatment chamber it has an initial motion conforming to the direction of whirling movement of the gaseous fluid in said chamber. The particles of material are picked up and carried forwardly around the axis of the treatment chamber, in the direction of this whirling movement (clockwise in Fig. 2). Due to centrifugal action, particles above a certain size are caused to move outwardly into the annular grinding zone and into the zones of action of the high velocity fluid jets delivered through the openings 14a, 15a, 16a, etc.

The following description of the action of the fluid jets will refer particularly to the jets introduced through the openings at the position A in Fig. 2, but it will be understood that the same description will also be applicable to the other sets of jets, such as those at B, C and D.

The jets introduced through the openings 14a and 15a in Fig. 1 in the upper portion Z of the grinding zone will impart a spiralling motion, similar to that of a right handed screw, to the

material accumulating along the torus-like surface defined by the curved wall portions 9 and 8, so as to direct such material into the path of the jet introduced through opening 16a. Similarly, the jets introduced through openings 14a' and 15a' will impart a spiralling motion, similar to that of a left-handed screw, to the material accumulating along the torus-like surface, defined by the curved wall portions 9' and 6' in the lower portion Z' of the grinding zone, so as to direct such material into the path of the jet introduced through opening 16a'.

While the several jet openings 14a, 15a, etc., are shown as located in the same radial plane 15 passing through the axis of the treatment chamber, this construction is shown primarily for the purpose of simplifying the illustration in Fig. 1, and would ordinarily be used only when the several sets of jet openings such as A, B, C, etc., 20 are disposed at sufficiently small angular intervals around the treatment chamber, so that the jets through the respective openings such as 14a and 15a, will serve to direct material into the path of a jet of the next set. When the design 25 of the apparatus does not contemplate the provision of a sufficiently large number of sets of jets to produce the above described result, a preferred arrangement would be to stagger the jet openings of each set so that the positions of the successive jet openings such as 14a, 15a and 16a of each set, will conform substantially to the path of the above described spiralling motion of the material along the torus-like surfaces of the upper and lower portions of the grinding zone. For 30 example, the jet opening 15a of each set would be angularly displaced from the jet opening 14a in the direction of whirling movement about the axis of the treatment chamber, and the jet opening 16a would be similarly displaced from the jet opening 15a. Such a staggered arrangement of the jet openings is described more fully herein-after in connection with Fig. 5.

Thus it will be seen that the fluid jets delivered through the openings, such as 14a and 15a, 14a' and 15a', will act upon material tending to accumulate through centrifugal action in the portions of the grinding zone which are at the greatest radial distance from the axis of the treatment chamber, and will positively direct some of this 50 material into the zones of action of the opposed jets, such as 16a and 16a'.

It will be seen that the jets issuing through the openings 16a and 16a' have relatively large opposed axial components of velocity, compared to their total velocity, so as to cause these jets to intersect one another at a relatively large angle and at a position relatively close to the jet openings, so that a large number of particles propelled by such jets will collide with high opposing axial components of velocities, providing an intense shattering effect. Although it will be seen that the jets issuing through openings 15a and 15a' may also have opposed axial components of velocity, such components are relatively small as compared to their total velocity, so that the issuing jets intersect at a relatively small angle and at a considerable distance from the jet openings. Hence, particles propelled by these jets are likely to suffer collisions with other particles in the grinding zone before reaching the position of intersection of the jet axes, and the jets issuing through openings 15a and 15a' will not function effectively to produce grinding by opposed jet action in the manner of the jets from openings 70 75

16a and 16a', and are not intended primarily for that purpose.

The material entering the paths of the opposed jets issuing from openings 16a and 16a' will be propelled at high velocity in the directions of such jets and will be subjected to grinding or size reducing action by impact and attrition resulting from the opposed axial components of velocity of colliding particles propelled by these two jets in the neighborhood of the position of 10 intersection of these jets, as indicated at X in Fig. 3. Due to the centrifugal action resulting from the general whirling motion of the contents of the treatment chamber around the axis thereof, the larger particles of material are then 15 caused to return to the peripheral portion of the grinding zone, where they are again acted upon by the jets issuing from the openings 14a, 15a, 14a' and 15a', while the particles which have been sufficiently reduced in size are carried inwardly due to the entraining action of the inwardly spiralling gas.

The jets issuing from openings 14a, 15a, 14a' and 15a' also contribute directly to the grinding action by imparting high velocities to material 25 intercepted thereby, and causing impact and attrition of such material with other particles of material circulating in the grinding zone, or against the walls of the treatment chamber. The material thus acted upon is also subjected to the 30 above described centrifugal classifying action, and the particles which are sufficiently reduced in size are entrained inwardly toward the gaseous fluid outlet of the treatment chamber.

It is evident that the fluid jets from the openings 14a, 15a and 16a in the upper portion of the grinding zone, and the jets from the openings 14a', 15a' and 16a' in the lower portion of the grinding zone, serve to superimpose upon the general whirling movement of the material 40 around the axis of the treatment chamber positive circulatory motions in radial planes passing through the axis of said chamber as indicated by the arrows in Fig. 1, and some of the material in the grinding zone will therefore have a composite spiralling motion conforming to that of a right handed screw in the upper portion, and a left handed screw in the lower portion of the grinding zone. It will also be seen that the curved peripheral wall portions of the treatment 50 chamber, which extend around and at both axial ends of the grinding zone, have cross-sections in radial vertical planes composed of arcs of circles around the centers, such as O and O', about which the superimposed circulatory motion in 55 such radial planes is produced by the fluid jets, so as to cooperate with the jets in maintaining the above described resultant screw-like motion of the material in the upper and lower portions of the grinding zone.

The particles of material entrained inwardly from the grinding zone by the inwardly spiralling gas, together with any particles of material entering through the material inlet openings 26 which are already of a sufficiently small size to 60 be so entrained, are carried with the whirling gas into the centrifugal product collector 21, where they are subjected to an intense centrifugal separating action, the material thus separated being discharged through the lower end of said 70 collector, while the gaseous fluid more or less freed of its burden of material is discharged through the central fluid outlet passage 22.

Fig. 4 is a vertical section of the outer portion of a modified form of grinding apparatus ac- 75

ording to this invention, taken in a radial vertical plane passing through its axis. This apparatus comprises a casing of circular cross-section enclosing a treatment chamber and including a top section 31 and a bottom section 31', flanged exteriorly at their meeting faces and secured together by means of tie bolts 32. The peripheral portions 33 and 33' of the top and bottom casing sections are curved so as to provide annular grinding zone Z'' at the outer portion of the treatment chamber enclosed at its periphery and at both axial ends by surfaces having an arcuate cross-section in a radial vertical plane passing through the axis of the treatment chamber.

15 A plurality of jet openings 34, 35, 36 and 37 are provided in the curved wall portions 33 and 33' at different angular positions about the center of curvature O'' of the above mentioned arcuate surfaces. All the openings of this set are shown 20 as positioned in a common radial vertical plane through the axis of the casing, that is, in the plane of Fig. 4. It will be understood that any suitable number of such sets of openings may be provided at different angular positions around 25 the axis of the casing in a manner comparable to that shown in Fig. 2 and it will also be understood that the successive openings 34, 35, etc., of each set may be angularly displaced from one another about the axis of the casing in a progressively advancing manner in the direction of 30 whirling movement about said axis as more fully described hereinafter. Each of the openings 34, 35, 36 and 37 has a component of direction inclined in one direction with respect to a radial 35 plane passing through the axis of the casing in order to maintain the whirling movement of the contents of the casing about the axis thereof, as described above in connection with Figs. 1 to 3, and each of these openings also has a component 40 inclined in one direction with respect to the radius of curvature of the inner surfaces of walls 33 and 33' in radial planes passing through the axis of the casing, as indicated by the dotted projection traces of the axes of said openings upon the plane of Fig. 4. This latter component 45 of direction of the fluid jets issuing from these openings serves to superimpose upon the whirling motion about the axis of the casing, a positive circulatory movement in radial planes passing 50 through said axis.

50 Any suitable means may be provided for supplying gaseous fluid under pressure to the above mentioned jet openings. The openings 34 and 35 are shown as provided in the curved wall portion 33' of the lower casing section 31' and the openings 36 and 37 in the curved wall portion 33 of the upper casing section 31. The respective casing sections are shown as provided with annular fluid pressure manifolds 38 and 38' disposed exteriorly of the curved wall portions 33 and 33' and communicating with the openings 36, 37 and 34, 35, respectively, and said manifolds are provided with fluid inlets 39 and 39' respectively.

55 The remaining portions of this apparatus may be substantially the same as above described, the annular material supply passage being shown at 41 and the material being delivered from said passage to the interior of the casing through openings such as 42 comparable to the openings 26 above described.

60 Except for the omission of axially opposed jets such as those issuing from the openings 16a and 16a' above, and the resultant intensified grinding action due to such opposed jets, the operation of this form of apparatus is similar to that

above described. Particles of solid material which are brought into the annular grinding zone by the action of centrifugal force are subjected to the action of the high velocity fluid jets delivered through openings 34, 35, 36 and 37. 5 These jets will impart a spiralling motion similar to that of a right-handed screw, to the material accumulating along and adjacent the torus-like surface defined by the curved wall portions 33 and 33' and particles of material entering 10 the paths of these jets will be propelled at high velocity in the direction of the jets and will be subjected to pulverizing action by impact and attrition due to collisions thereof with other particles of material circulating in the grinding 15 zone or against the walls of the chamber. Due to the component of positive circulatory motion in radial planes passing through the axis of the chamber, which is superimposed upon the general whirling motion about the axis of the casing to 20 provide the above mentioned screw like motion, the material is prevented from simply whirling around adjacent the peripheral walls in planes removed from the positions of the jets and is 25 repeatedly picked up by the jets and positively directed into the zones of action of other jets either of the same set or of a succeeding set around the axis of the casing.

30 As in the form of apparatus first described, the gaseous fluid undergoes an inwardly spiralling action toward the centrally disposed fluid outlet, resulting in a continual classification of the material in the grinding zone by the combined actions of centrifugal force and the inward entraining effect of the gas, so that particles which 35 have been sufficiently reduced in size are carried inwardly and removed from the grinding zone while larger particles are returned toward the peripheral portion of the grinding zone for further action by the fluid jets.

40 Fig. 5 is a partial plan view of the apparatus similar to that shown in Fig. 4 and illustrates the above mentioned preferred arrangement of the jet openings of each set in cases where the successive sets of jet openings are not disposed 45 at sufficiently small angular intervals around the treatment chamber so that the jets delivered through one set of openings will direct material into the paths of jets of the next set. In this figure a set of four jet openings is indicated at 30 34a, 35a, 36a and 37a, the upper fluid pressure manifold 38 being partly broken away as indicated at 44 to better show the openings 36a and 37a in the upper curved wall portion 33 of the casing, and the upper casing section 31 being 50 partly broken away as indicated at 45 to better show the openings 34a and 35a in the curved wall portion 33' of the lower casing section 31'. This view illustrates the inclination of the axes of the respective jet openings with respect to radial 55 planes passing through the axis of the casing as indicated by dotted lines representing the projection traces of the respective jet axes on the plane of the figure, and the directions of these 60 components of inclination of these openings as 65 thus illustrated may be taken as illustrative of the corresponding components of inclination of jet openings 34 to 37 in Fig. 4. Similarly, it will be understood that the jet openings 34a to 37a also have components of inclination in one direction with respect to radii of curvature of the 70 wall portions 33 and 33' in radial planes passing through the axis of the casing comparable to the components of inclination represented by the dotted projection traces of the openings 34 to 37 75

in Fig. 4. In this case, however, the jet openings are shown as staggered or angularly displaced from one another about the axis of the casing so that the positions of the successive openings 34a, 35a, etc., conform substantially to the path of the above described screw-like motion of the material along the torus-like surface of the grinding zone. Thus the jet opening 35a, which succeeds the jet open 34a in the direction 10 of the superimposed circulatory motion in radial planes through the axis of the casing, is angularly displaced from the opening 34a in the direction of whirling movement about the axis of the casing in such manner that material propelled by the fluid jet from opening 34a will be directed into the path of the fluid jet from the opening 35a as may be seen by comparing the dotted projection traces of the jets 34 and 34a in Figs. 4 and 5. Similarly the jet openings 36a 20 and 37a are offset angularly about the axis of the casing with respect to the preceding jet openings 35a and 36a respectively. The first jet opening of a succeeding set may be located, for example, as indicated at 38b, the position and 25 direction thereof corresponding to opening 34a and being angularly off-set from opening 37a in the direction of whirling movement around the axis of the casing.

Such an arrangement of the jet openings will 30 serve to provide an effective pulverizing action on the material due to direct collision or impact of particles propelled by one jet with particles propelled by another jet and will also serve to bring a high proportion of the material in the 35 grinding zone into the zones of action of the successive jets. It will be understood that a similar off-set or staggered arrangement of the jet openings of each set around the axis of the casing may also be applied to the jet openings of each 40 set in the upper and lower portions of the grinding zone, in the form of apparatus shown in Figs. 1 to 3.

In the form of apparatus illustrated in Fig. 4 or Fig. 5, it will be understood that the sets of jet 45 openings disposed at different angular positions around the axis of the treatment chamber may have oppositely directed components of inclination with respect to radii of curvature of the walls in radial planes passing through said axis, so that some of the sets of jets serve to produce 50 a right-handed screw-like spiralling motion and other sets of jets serve to produce a left-handed screw-like spiralling motion.

Also, it will be understood that in any of the 55 forms of the apparatus shown, some of the jet openings may be of different size than other jet openings, and that separate fluid pressure manifolds or passages may be provided for supplying gaseous fluid at different pressures to different jet openings.

It will be seen that according to the present invention all of the fluid jets introduced into the grinding zone are given components of velocities normal to the adjacent wall portions of the treatment chamber. In this manner the high velocity 65 range of the issuing jets, bringing about the maximum impact forces, is dissipated in regions removed from the walls of the chamber which minimizes frictional wear of the walls. Furthermore, 70 it will be evident that any plane passing through the axis of a jet would have substantially an equal amount of gaseous fluid flowing on either side thereof. This excludes the possibility of using jets whose axes are truly tangent to the periphery 75 of the treatment chamber, since with such a jet,

a median plane through the jet axis would be tangent to the periphery of the chamber so that approximately half of the gaseous fluid would be diverted to the outside of the chamber instead of into the interior thereof. Such a construction is 10 clearly impossible since the invention contemplates that all the fluid should be introduced into the interior of the treatment chamber and preferably in such manner that the highest velocity portion of the jet adjacent a jet opening does not 15 sweep against the walls of the treatment chamber. This greatly reduces the wear at the walls while the grinding efficiency of the jets is not appreciably reduced and is in many cases materially increased. 15

I claim:

1. In a centrifugal fluid jet pulverizing apparatus for pulverizing solid materials by impact and attrition of particles upon one another, the combination of a casing of circular cross-section enclosing an annular grinding zone in the outer portion thereof, said casing having peripheral walls extending around and at both axial ends of said grinding zone and curved in radial planes passing through the axis of the casing to provide a 25 surface of arcuate cross-section in such radial planes, said peripheral walls being provided with jet openings for introducing high velocity fluid jets into said grinding zone in directions having components inclined forwardly in one direction 30 with respect to such radial planes in order to maintain whirling motion about said axis, said jet openings including at least one set comprising a plurality of openings located at different angular positions about the center of curvature of said 35 arcuate surface in such radial planes and the components of direction, in such radial planes, of all of the openings of said set being inclined in one direction with respect to the radii of curvature of said arcuate surface at the positions of 40 the respective openings and being inclined at different angles with respect to the axis of the casing, whereby the fluid jets issuing from the differently located and directed openings of said set will cooperate to superimpose upon such whirling 45 motion a positive circulatory motion in such radial planes, and means for supplying gaseous fluid at high pressure to said jet openings. 55

2. In a centrifugal fluid jet pulverizing apparatus for pulverizing solid materials by impact and attrition of particles upon one another, the combination of a casing of circular cross-section enclosing an annular grinding zone in the outer portion thereof, said casing having peripheral walls extending around and at both axial ends of said grinding zone and provided with jet openings for introducing high velocity jets into said grinding zone in directions having components inclined forwardly in one direction with respect to radial planes passing through the axis of said casing in order to maintain whirling motion about said axis, said jet openings including a plurality of angularly spaced pairs of openings located substantially opposite one another in a direction parallel to said axis and inwardly from the outer periphery of the grinding zone, the respective openings of each such pair having opposed components of direction parallel to said axis and being so directed that the opposed fluid jets issuing therefrom will intersect one another at positions inwardly removed from the outer periphery of the grinding zone, and said jet openings also comprising other openings which are located at greater radial distances from said axis than said oppositely located openings and which are so positioned and directed 60 65 70 75 75

that the fluid jets issuing therefrom will have components of velocity inclined with respect to the components of velocity of said opposed jets, in radial planes passing through said axis, and will superimpose upon the whirling motion about the axis of the casing, within the respective axial end portions of said grinding zone, opposite circulatory motions in such radial planes in such manner as to act upon material adjacent the periphery of the grinding zone and positively direct such material into the paths of said opposed jets, and means for supplying gaseous fluid under pressure to said jet openings.

3. In a centrifugal fluid jet pulverizing apparatus for pulverizing solid materials by impact and attrition of particles upon one another, the combination of a casing of circular cross-section enclosing an annular grinding zone in the outer portion thereof, said casing having peripheral walls extending around and at both axial ends of said grinding zone, the portions of said peripheral walls adjacent the respective axial ends of the grinding zone being curved in radial planes passing through the axis of the casing to provide two surfaces having arcuate cross-sections in such radial planes and whose centers of curvature in such radial planes are axially spaced from one another, said peripheral walls being provided with jet openings for introducing high velocity jets into said grinding zone in directions having components inclined forwardly in one direction with respect to radial planes passing through the axis

of said casing in order to maintain whirling motion about said axis, said jet openings including a plurality of angularly spaced pairs of openings located substantially opposite one another in a direction parallel to said axis and inwardly from the outer periphery of the grinding zone, the respective openings of each such pair having opposed components of direction parallel to said axis and being so directed that the opposed fluid jets issuing therefrom will intersect one another at positions inwardly removed from the outer periphery of the grinding zone, and said jet openings also comprising a plurality of other openings which are located at a plurality of different angular positions about said center of curvature of each of said arcuate surfaces and at greater radial distances from said axis than said oppositely located openings, and which are so positioned and directed that the fluid jets issuing therefrom will have components of velocity inclined with respect to the components of velocity of said opposed jets, in radial planes passing through said axis, and will superimpose upon the whirling motion about the axis of the casing, within said respective axial end portions, opposite circulatory motions in such radial planes in such manner as to act upon material adjacent the periphery of the grinding zone and positively direct such material into the paths of said opposed jets, and means for supplying gaseous fluid under pressure to said jet openings.

ALBERT C. HOBBIE.
